HINGE

Maurice Rainville, Manville, R. I.

Application February 5, 1937, Serial No. 124,298

1 Claim. (Cl. 16—128)

The present invention relates to a hinge for doors and the like and has for its primary object to provide a hinge whereby only one is necessary to mount a door or the like.

5 Another very important object of the invention resides in the provision of a hinge which is easily and quickly assembled and disassembled.

A still further important object of the invention resides in the provision of a hinge of this nature which is comparatively inexpensive to manufacture, strong and durable, thoroughly efficient and reliable in use and otherwise well adapted to the purpose for which it is designed.

With the above and numerous other objects 15 in view as will appear as the description proceeds, the invention consists in certain novel features of construction, and in the combination and arrangement of parts as will hereinafter be more fully described and claimed.

20 In the drawings:—

Figure 1 is a fragmentary sectional view through a stationary and swingable member showing the hinge in top plan.

Figure 2 is a front elevation of the hinge.

25 Figure 3 is a sectional view taken through a portion of the hinge.

Figure 4 is a sectional view taken on the line 4—4 of Figure 3.

Figure 5 is a detail view of the ball.

30 Letter A denotes the stationary member and letter B a swingable member. Letter C denotes generally the hinge.

The hinge comprises a pair of plates 5 and 6 the former secured to the stationary member A and the latter secured to the swingable member B. The plate 5 is provided with a pair of spaced arms 7—7 having upwardly facing sockets 8—8 of a semi-spherical formation. On the plate 6 there are a pair of arms 9—9 terminating in 35 downwardly facing semi-spherical sockets. Balls 11—11 are mounted in the sockets 8—8 and the sockets 10—10 rest on the balls 11—11. The sockets 8—8 and 10—10 are secured to the balls 11—11 by means of screws 12.

With this construction it will be seen that a door or the like may be mounted just using one hinge and will swing easily because of the balls. It is thought that the construction, operation, utility and advantage of the invention will be 5 now clearly understood without a more detailed description thereof.

The present embodiment of the invention has been described in considerable detail merely for the purposes of exemplification since in actual 10 practice it attains the features of advantage enumerated as desirable in the statement of the invention and the above description.

Having described the invention what is claimed as new is:—

In a hinge for securing a door to a side stile of a door frame, a pair of elongated complementary plates adapted for attachment to the face of the door and stile, respectively, adjacent to opposed edges thereof in side-by-side relation 20 and extending longitudinally of said door and stile, each plate embodying a pair of vertically spaced arms curving toward the contiguous edges of said plates and terminating in a pair of semi-spherical sockets, the pairs of sockets opening 25 in opposite directions, respectively, to form upper and lower pairs mating in superposed relation, the arms of each pair of mating sockets extending therefrom obliquely upwardly and downwardly, respectively, to embrace the same against 30 stress and strain resulting from the weight of the door and forming at their junctures with said sockets reinforcing portions of increased thickness around the centers of said sockets, a ball interposed between each pair of mating sockets 35 and snugly fitting therein, and a pair of studs passing through the reinforcing portions of each mating pair of sockets in the axis of the related ball, said studs being threaded into the ball and pivoting in said portions whereby said sockets 40 and balls are relatively rotatable.

MAURICE RAINVILLE.
